CLAIM

The ornamental design for a reference indicator patch for use in an automated reference indicator system for photographic and video images, as shown and described.

DESCRIPTION

FIG. 1 is a perspective view of a reference indicator patch showing our design.

FIG. 2 is a front elevational view thereof.

FIG. 3 is a side view thereof, the side view being identical from all directions; and,

FIG. 4 is a rear elevational view thereof having a bonding material thereon.

The shading of FIGS. 1 and 2 is intended to be symbolic of color contrast.
